UNITED STATES PATENT OFFICE

111,887

DESIGN FOR A SCRUBBING MACHINE

John A. Backlund, Chicago, Ill., assignor to Lincoln-Schlüter Floor Machinery Company, Inc., Chicago, Ill., a corporation of Illinois

Application May 20, 1938, Serial No. 77,293

Term of patent 14 years

To all whom it may concern:

Be it known that I, John A. Backlund, a citizen of the United States, residing at Chicago, in the county of Cook and State of Illinois, have invented a new, original, and ornamental Design for a Scrubbing Machine, of which the following is a specification, reference being had to the accompanying drawings, forming part thereof, in which:

Figure 1 is a view in perspective of the front

and one side of a scrubbing machine showing my new design; and

Figure 2 is a view in perspective of the other side and rear thereof.

The dominant features of my design reside in the portions shown in full lines.

I claim:

The ornamental design for a scrubbing machine, substantially as shown and described.

JOHN A. BACKLUND.
